Primary Examiner—Susan Bennett Hattan
(74) *Attorney, Agent, or Firm*—Tracy P. Jong(57) **CLAIM**

The ornamental design for a dispensing cap for a water bottle, as shown.

DESCRIPTION

FIG. 1 is a front perspective view of a dispensing cap for a water bottle cap showing the ornamental design of the exterior surface of the cap.

FIG. 2 is a front orthogonal view of the dispensing cap depicted in FIG. 1.

FIG. 3 is a rear orthogonal view thereof.

FIG. 4 is a left side orthogonal view thereof.

FIG. 5 is a right side orthogonal view thereof.

FIG. 6 is a top plan view thereof.

FIG. 7 is a bottom plan view thereof; and,

FIG. 8 is a front perspective view of the dispensing cap depicted in FIG. 1 mounted for use on a water bottle.

The subject matter in broken lines is shown for clarification and forms no part of the claimed design subject matter.
